DISPLAY STAND

Frederic C. Muntwyler, Palos Park, Ill.

Application November 2, 1954, Serial No. 466,286

5 Claims. (Cl. 248—197)

This invention relates to a new and improved easel or display stand comprising a display panel and supporting leg structure therefor.

It is a general object of the invention to provide a new and improved display device of the type described which is inexpensive to construct and provides a more firm support than prior art devices.

In prior constructions, display stands have included a display panel supported by legs secured to the panel by means of threaded connections. Since display stands are often moved from place to place and frequently assembled and disassembled, the use of threaded connections is time consuming and the parts are subject to considerable wear. In the present construction, the panel is supported by leg structure which may be readily attached and detached without the use of screws, and it is a more particular object of the invention to provide a display stand wherein the panel and supporting leg structure are assembled manually and are securely held together by closely interfitting means on the panel and leg structure which require that in assembling the parts the leg structure be biased to fit its co-operating means on the panel whereby, when assembled, the panel and leg structure are securely connected, and whereby added weight on the display panel tends to bind the supporting leg structure more securely to the panel.

It is also an object of the invention to provide a new and improved stand of the type described including a panel having a frame around the edge of a lower portion thereof, the frame having adjacent each bottom corner thereof a downwardly extending projection and in each side portion thereof one or more recesses extending upwardly and inwardly from the outer edge thereof and a supporting leg structure for each side of the frame, each of the leg structures comprising a pair of legs diverging downwardly and forwardly and rearwardly from a position adjacent said recesses and having portions at their upper ends detachably fitting in said recesses, and a transverse rod extending between lower portions of said legs in a front to rear direction with respect to the frame and having a portion interconnecting with one of said projections.

Other objects and advantages will become readily apparent from the following detailed description, taken in connection with the accompanying drawings, in which:

Fig. 1 is a front view of a display stand embodying my invention;

Fig. 2 is a fragmentary side elevation taken from the right of Fig. 1;

Fig. 3 is a fragmentary exploded front view; and

Fig. 4 is a fragmentary bottom plan view taken on the line 4—4 of Fig. 2.

The invention further resides in the combination, construction and arrangement of parts illustrated in the accompanying drawings, and while I have shown therein a preferred embodiment, I wish it understood that the same is susceptible of modification and change within the scope of the appended claims.

2

Referring now to the drawings, the invention as disclosed herein is embodied in a stand including a display panel 2 which may be provided with a plurality of apertures 4 arranged in any desirable pattern and adapted 5 to receive pegs which may be utilized to support a variety of articles for display. The display panel 2 may be provided with a frame extending around the outer edge thereof, the frame including a bottom portion 6 and side portions 8.

10 On the bottom face of the bottom portion 6 of the frame, adjacent each side portion 8, there is provided a groove 10 extending in a direction from front to rear with respect to the panel to define a downwardly extending projection 12 at each bottom corner of the frame. The side portions 8 are provided with recesses extending angularly upwardly and inwardly from the outer edge of the frame. As shown, each of the side portions 8 is provided with a pair of opposed recesses 14, arranged in the front and rear faces respectively of the side portion 8, and spaced upwardly from the bottom portion 6 of the frame. The grooves 10 and the recesses 14 are adapted to receive closely interfitting portions of the supporting leg structure to be described presently.

The display panel is adapted to be held by a supporting leg structure 16 provided at each side of the panel. Each of the supporting leg structures comprises a pair of legs 18 and 20 diverging downwardly and, forwardly and rearwardly respectively, from a position adjacent the recesses 14 and each of the legs 18 and 20 is provided 25 with an angularly bent portion 22 at its upper end. The angularly bent portions 22 are adapted to be fitted respectively into the recesses 14 when the display stand is assembled. The legs 18 and 20 may be rigidly connected near their upper ends by means of a transverse rod 24 extending in a front to rear direction with respect to the panel. The legs 18 and 20 are rigidly connected near their bottom ends by means of a rod 26. As shown, the leg 18 which extends forwardly from the panel is slightly longer than the rearwardly extending leg 20 and the transverse rod 26 is connected at its opposite ends to the legs 18 and 20 at points equidistantly spaced from the upper ends of the legs. In this manner, as will appear, the panel 2 is maintained in a plane slightly inclined upwardly and rearwardly to facilitate the display. Each of the transverse rods 26 is provided at its mid portion with a rigidly secured U-shaped bracket 28 adapted to embrace the adjacent projection 12 on the bottom of the frame when the leg structure is attached to the panel.

While the leg structure and the frame are closely interfitted and securely connected when assembled as shown in Fig. 1, for example, the leg structure is constructed so that it must be biased to simultaneously fit its cooperating projection 12 and recesses 14 on the panel. To this end, when the leg structure is detached, the interior angle defined by the angularly bent portions 22, with the vertical portions of the legs, is greater than the angle defined by the recesses 14 with the outer edge of the frame portion 8 extending therebelow. In one embodiment, for example, the latter angle is about 135 degrees and the former a few degrees greater. Thus, as the angularly bent portions 22 on the legs 18 and 20 are slidably fitted into the recesses 14 by an upward and inward motion, the lower portion of the legs is bent inwardly toward the middle of the bottom portion 6 of the frame in order that the U-shaped bracket 28 may be fitted over the projection 12 and seated in a home position. The legs 18 and 20 may be constructed of any relatively rigid material such as wire rod, for example, which has a degree of flexibility to permit its assembly as described.

70 In this manner, the panel frame and the leg structure are securely fastened together, the panel being supported

by the angularly bent portions 22 of the legs as well as by the U-shaped brackets 28. The brackets 28, being latched over the projection 12, also serve to prevent any lateral movement of the leg structure 16 with respect to the panel 2. Any added weight, placed on the panel 2 by objects displayed thereon, bears on the leg portions 22 and tends to spread the legs outwardly as viewed in Fig. 1 and thus binds the bracket 28 more securely to the projection 12.

By virtue of the fact that the legs 18 are longer than the legs 20, the panel is inclined upwardly and rearwardly, and the center of gravity of the stand is spaced rearwardly of the mid-point between the bottom ends of the legs 18 and 20. The stand, however, is intended for use primarily in displaying articles of considerable weight, which, when supported on pegs in the apertures 4, extend forwardly of the panel and tend to move the center of gravity forwardly and thus add greater stability to the stand when placed in use.

I claim:

1. A display stand adapted to be assembled and disassembled and held together solely by closely interfitting means on its components comprising, in combination: a generally vertically arranged display panel having a frame around the outer edge thereof, said frame having, in the bottom edge thereof, adjacent each corner, a groove extending in a front to rear direction to define a downwardly extending projection having a square cross section, said frame also having, in each side portion thereof of above the bottom, in the front and rear faces, respectively, recesses extending angularly upwardly and inwardly from the outer edge of the frame; and a supporting leg structure for each side of the frame, each of said leg structures comprising a pair of legs disposed in a vertical plane and diverging downwardly and, forwardly and rearwardly respectively, from a position adjacent said recesses, said forwardly extending leg being longer than the rearwardly extending leg, each of said legs having an angularly bent portion at its upper end, said angularly bent portions being detachably fitted respectively in said recesses, a transverse rod extending in a front to rear direction and rigidly connecting said legs near their upper ends, a lower transverse rod extending in a front to rear direction and rigidly connected to said legs near their lower ends at points equidistantly spaced from the upper ends of said legs, and a U-shaped bracket secured to the midportion of said lower transverse rod and embracing the adjacent downwardly extending projection on said frame, the interior angle defined by said angularly bent portions of said legs with the vertical portions of said legs, when disassembled, being greater than the angle defined by said recesses with the outer edge of said frame extending therebelow, whereby said leg structures must be biased during assembly in order for said U-shaped portions on said lower transverse rods to embrace said downwardly extending projections on said frame.

2. A display stand adapted to be assembled and disassembled and held together solely by closely interfitting means on its components comprising, in combination: a generally vertically disposed display panel having a frame around the outer edge of a lower portion thereof, said frame having, at the bottom, adjacent each corner, a downwardly extending projection, said frame also having, in each side portion thereof above the bottom, in the front and rear faces, respectively, recesses extending angularly upwardly and inwardly from the outer edge of the frame; and a supporting leg structure for each side of the frame, each of said leg structures comprising a pair of legs disposed in a vertical plane and diverging downwardly and, forwardly and rearwardly respectively, from a position adjacent said recesses, each of said legs having an angularly bent portion at its upper end, said angularly bent portions detachably fitting respectively in said recesses, a transverse rod extending in a front to rear direction and connecting said legs near their lower ends, and a U-shaped portion on said transverse rod interconnecting with the adjacent downwardly extending projection on said frame.

3. A stand adapted to be assembled and disassembled comprising, in combination: a generally vertically disposed panel having a frame around the outer edge thereof, said frame having, in the bottom edge thereof, adjacent each corner, a groove extending in a front to rear direction to define a downwardly extending projection, said frame also having, in each side portion thereof above the bottom, in the front and rear faces, respectively, recesses extending angularly upwardly and inwardly from the outer edge of the frame; and a supporting leg structure for each side of the frame, each of said leg structures comprising a pair of legs disposed in a vertical plane and diverging downwardly and, forwardly and rearwardly respectively, from a position adjacent said recesses, said forwardly extending leg being longer than the rearwardly extending leg, each of said legs having an angularly bent portion at its upper end, said angularly bent portions detachably fitting respectively in said recesses, a transverse rod extending in a front to rear direction and connecting said legs near their upper ends, a lower transverse rod extending in a front to rear direction and connecting said legs near their lower ends at points equidistantly spaced from the upper ends of said legs, and a bracket on said lower transverse rod embracing the adjacent downwardly extending projection on said frame.

4. A display stand comprising, in combination: a display panel having a frame around the outer edge of a lower portion thereof said frame having, at the bottom, adjacent each side portion thereof a downwardly extending projection, said frame also having, in each side portion thereof above the bottom, recesses extending angularly upwardly and inwardly from the outer edge of the frame; and a supporting leg structure for each side of the frame, each of said leg structures comprising a pair of legs in a vertical plane diverging downwardly and forwardly and rearwardly, respectively, from a positive adjacent said recesses, each of said legs having an angularly bent portion at its upper end, said angularly bent portions detachably fitting respectively in said recesses, a transverse rod extending in a front to rear direction and connecting said legs near their lower ends, and a U-shaped portion on said transverse rod interconnecting with the adjacent downwardly extending projection on said frame.

5. A display stand comprising, in combination: a generally vertically disposed display panel having downwardly extending projections at the bottom adjacent opposite side portions, and recesses in the side portions above the bottom extending upwardly and inwardly from the outer edge of the panel; and a supporting leg structure for each side of the panel comprising a pair of legs diverging downwardly and, forwardly and rearwardly respectively and having portions at their upper ends detachably fitting in said recesses, and a transverse rod extending between lower portions of said legs in a front to rear direction with respect to the panel and having a U-shaped portion interconnecting with the adjacent downwardly extending projection to prevent vertical and lateral movement of the leg structure with respect to the panel when so connected and when the upper portions of said legs are fitted in said recesses.
